UNITED STATES PATENT OFFICE

FRANK G. WIKSTROM, OF BROOKLYN, NEW YORK, ASSIGNOR TO HADWIK MFG. CO., INC., OF NEW YORK, N. Y., A CORPORATION OF NEW YORK

CLOSURE

Application filed December 21, 1927. Serial No. 241,484.

This invention relates to closures for containers, and is herein shown applied to a metallic barrel head, although it may, of course, be used in any container wall.

5 One of the objects of the invention is to provide an improved closure or cap in which the component elements are so designed as to enable them to be economically and otherwise satisfactorily made by stamping operations and to provide a closure which is strong, durable and reliable in use. Another object is to provide a new and improved cap adapted for the reception of sealing means.

The invention will be understood from the 15 following description taken in connection with the accompanying drawing in which Figure 1 is a plan view of the cap; Figure 2 is a central, vertical, sectional view of the cap showing it threaded into a suitable sput 20 or cap seat interlocked with a container wall; and Figure 3 is a plan view of a metal tab adapted to be anchored in place intermediate the folds of the double-lock seam, as shown in Figure 2, and to serve as a securing member for a sealing wire.

Referring to the drawings, the numeral 10 indicates a barrel head provided with a suitable bung sput 11, herein shown as constructed from sheet metal and having interlocking engagements with the barrel head at 12. The sput 11 is provided with a depending internally screw threaded flange 13, adapted to receive the screw threaded element of the closure embodying this invention. 30 This sput construction (without the seal attaching means hereinafter mentioned) is described and claimed in my co-pending application Ser. No. 222,409 filed September 28, 1927.

40 The closure is made up of two primary parts, namely, a sheet metal cup-shaped member 15 and a sheet metal cover plate or top member 16. The cup-shaped member 15 is provided on its cylindrical portion with screw threads adapted for engagement with the internally screw threaded flange 13 of the sput. The flat end wall 17 of the cup-shaped member may be provided with a plurality of projections 18, which are struck up from the 45 wall by suitable dies, the dies being prefer-

ably so constructed that the metal forming the projections is sheared from the metal of the wall 17 with the result that the projections 18 are in the form of metal slugs which 55 tightly fit the openings 19 within which they are frictionally held. These projections 19 are adapted to fit into a plurality of depressions 21 formed in the cover plate 16 in proper relation to receive the projections 18, the depressions being formed by suitable dies as will be readily understood. The projections 18 and the depressions 21 by their interlocking engagement with each other serve to prevent the cover plate 16 from turning with respect to the cup-shaped member 15, when the closure is being applied to or removed from the sput 11. The bottom of the cup-shaped member 15 is adapted to engage throughout its entire area the central portion of the cover plate 16 as shown in Figure 2; and the cup-shaped member 15 is united to the cover plate 16 by welding as shown at 22 at a spot centrally of the group of depressions 21. The cover plate is bent down about the cylindrical portion of the cup-shaped member 15, so as 60 to provide a pocket or depression 24 into which the closed end of the cup-shaped member is adapted to fit. The relation of the pocket 24 to the cup-shaped member 15 is such that centralization of the cup-shaped 65 member with respect to the cover plate 16 is assured during assembling. The cover plate 16 is formed with an outwardly projecting flange portion 25 which serves as a gasket seat or gasket supporting portion, adapted 70 for the reception of a gasket 26 which is clamped into firm engagement with the gasket seat 27 of the sput 11 intermediate the screw threaded portion 13 thereof and its 75 outwardly and downwardly inclined wall 28. The flange 25 terminates in a downwardly and outwardly projecting apron 29 which serves to reinforce the cover plate 16 against distortion, particularly when the closure is being applied to the sput 11, and carries at 80 its lower edge a plurality of outwardly and upwardly projecting wrench receiving ears 30. These ears also serve as sealing lugs and are each provided with an opening 31 adapted 85 to receive the wire of a seal 32 which may 90

95 100

be passed through the perforated end of a sealing tab 33, one end of which is confined as shown in Figure 2 in the interlocking connection between the barrel head 10 and the sput 11.

5 While only one form of the invention is herein shown and described, it will be understood that various changes may be made without departing from the spirit of the invention or the scope of the following claims.

10 What is claimed is:

1. A container closure comprising a sheet metal cup-shaped member having an end wall and provided with screw threads on its cylindrical portion, and a sheet metal top member adapted to receive in abutting relation thereto the end wall of said cup-shaped member, said top member having a gasket supporting portion extending outwardly therefrom in 15 the vicinity of the point of peripheral engagement of the cup-shaped member with the top member, said gasket supporting portion carrying at its outer margin an apron terminating at spaced points in wrench-receiving ears 20 adapted to facilitate rotation of the closure in applying it to and removing it from a container, said top member and the end wall of 25 said cup-shaped member being welded together.
- 30 2. A closure comprising a sheet metal cup-shaped member having an end wall provided with slugs struck up therefrom and serving as interlocking elements, said cup-shaped member being provided with screw threads on its cylindrical portion, and a sheet metal top member adapted to receive in abutting relation thereto the end wall of said cup-shaped member, said top member having depressions formed therein in which said interlocking 35 elements fit and having a gasket supporting portion extending outwardly therefrom in the vicinity of the point of peripheral engagement of the cup-shaped member with the top member, said gasket supporting portion carrying at its outer margin an apron terminating 40 at spaced points in wrench receiving ears adapted to facilitate rotation of the closure in applying it to and removing it from a container, said top member and the end portion 45 of said cup-shaped member being welded together.
- 50 3. A container closure comprising a sheet metal cup-shaped member having a round flat end portion and provided with screw threads on its cylindrical portion, and a sheet metal top member having a depression having a round flat-bottom and into which the round flat end portion of said cup-shaped member fits with its round flat end portion in abutting 55 relation to and throughout the area of the round flat bottom of the depression in said top member, said top member also having a gasket supporting portion extending outwardly from the edge of the depression and an apron extending at an angle to said gas-

ket supporting portion, said apron having extending therefrom a plurality of perforated ears, the round flat bottom of the depression in said top member and the round flat-end portion of said cup-shaped member being welded together.

60 In testimony whereof, I have affixed my signature to this specification.

FRANK G. WIKSTROM.
